CLAIM

The ornamental design for an interbody device as shown and described.

DESCRIPTION

FIG. 1 is a top front perspective view of the interbody device;

FIG. 2 is a bottom rear perspective view of the interbody device of FIG. 1;

FIG. 3 is a front elevation view of the interbody device of FIG. 1;

FIG. 4 is a rear elevation view of the interbody device of FIG. 1;

FIG. 5 is a right elevation view of the interbody device of FIG. 1;

FIG. 6 is a left elevation view of the interbody device of FIG. 1;

FIG. 7 is a top plan view of the interbody device of FIG. 1;

FIG. 8 is a bottom plan view of the interbody device of FIG. 1; and,

FIG. 9 is an enlarged view of a portion of the interbody device of FIG. 1.

Portions of the claimed surface of the interbody device are illustrated with surface shading to indicate surface texture. The interbody device to which the ornamental design has been applied is for use in a spinal fusion procedure in which the interbody device is inserted between adjacent vertebrae. The interbody device is not limited to the scale shown herein.

The broken lines showing portions of an interbody device are provided for the purpose of illustrating portions which form no part of the claimed design.
